United States Patent Office

Des. 183,309
Patented Aug. 5, 1958

183,309

COMBINED BOTTLE AND CAP OR SIMILAR ARTICLE

Edward Hack, London, England, assignor to Flip Limited,
London, England

Application August 12, 1957, Serial No. 47,329

Term of patent 14 years

(Cl. D58—9)

FIG. 1

FIG. 3

Fig. 1 is a view in elevation of one side of a combined bottle and cap or similar article, showing my new design.

Fig. 2 is a view in elevation of the opposite side thereof; and

Fig. 3 is a top plan view thereof.

I claim:

The ornamental design for a combined bottle and cap or similar article, as shown.
